FIG. 5

Inventor

Edward P. Le Compte
By William D. Deane
his Attorney

UNITED STATES PATENT OFFICE.

EDWARD P. LE COMPTÉ, OF PARK CITY, UTAH.

CLOTHES-DRYING APPARATUS.

1,371,563.

Specification of Letters Patent. Patented Mar. 15, 1921.

Application filed December 17, 1918. Serial No. 267,095.

To all whom it may concern:

Be it known that I, EDWARD P. LE COMPTÉ, a citizen of the United States, residing at Park City, in the county of Summit and State of Utah, have invented certain new and useful Improvements in Clothes-Drying Apparatus, of which the following is a specification.

My present invention has to do with clothes drying apparatus.

One of the objects of the invention is the provision of a clothes drying apparatus that is extremely simple and inexpensive, is susceptible of being quickly and easily operated and is possessed of high efficiency in that the house wife or laundress is enabled to make the drying operation a continuing operation—*i. e.*, can place pieces of clothes on the line in succession and move the same away from and toward the point at which she stands so that when the first piece comes back in a dried state it may be removed from the return stretch of the line, and then when the outgoing and return stretches of the line are fed forwardly, a fresh piece of clothes may be fastened upon the inner portion of the outgoing stretch. This capacity of function is largely due to the pendent character of the sheave and sheave carrier embodied in the apparatus, the line being carried around the sheave in such manner that there is no interference from the pieces of clothes hung on the line.

Another object of the invention is to include the improvement indicated in an apparatus which comprises a casing, a drum mounted therein and a line movable into and out of the casing and formed in part of rope and partly of wire, joined end to end, whereby when the rope is not in use for drying clothes it may be entirely inclosed in the casing so as to preclude the deposit of dust and dirt on the rope and the subsequent objectionable transfer of the same to the freshly laundered pieces of clothes.

Other objects and practical advantages of the invention will be fully understood from the following description and claims when the same are read in connection with the drawings, accompanying and forming part of this specification, in which:

Figure 1 is a vertical longitudinal section, partly in side elevation, of the complete apparatus constituting the best practical embodiment of my invention that I have as yet devised.

Fig. 2 is a transverse section taken in the plane indicated by the line 3—3 of Figure 1, and showing the casing and the drum mounted in and inclosed by the casing together with the preferred arrangement of the combination rope and wire cable on the drum.

Fig. 3 is a plan view of the complete apparatus.

Fig. 4 is a vertical transverse section, on an enlarged scale, taken through the sheave and its carrier in the plane indicated by the line 4—4 of Fig. 1.

Fig. 5 is a view of the line or cable *per se*.

Similar numerals of reference designate corresponding parts in all of the views of the drawings.

In carrying my invention into effect I provide a stationary casing 1 in the front wall 2 of which are two spaced apertures 3 for the passage of the line stretches; the said apertures 3 being slightly larger in diameter than the casing with a view to lessening the liability of dust and dirt gaining access to the interior of the casing.

At a suitable distance from the casing 1, I locate a stationary pole or upright 4 which is preferably, though not necessarily, taller than the casing in about the proportion illustrated.

Journalized in the casing 1 is a drum 5, properly arranged opposite and relative to the apertures 3, and provided with a crank 90 6 whereby it may be readily rotated about its axis, though it is to be understood that any other approved means for the manual turning of the drum may be employed without affecting my invention. Coiled upon the 95 drum 5 and passed loosely through the casing apertures 3 is the line or cable of the apparatus which line or cable is made up of a length of rope 7 and a length of wire 8; the same being joined end to end as 100 shown diagrammatically in Fig. 5.

The line or cable is passed around the pendent sheave 9 which because of its shape and arrangement constitutes a highly important feature of my invention. The said 105 sheave 9 is tapered from its base to its upper end where it is provided with a guard flange 10. A longitudinal central bore 11 is formed in the sheave for the reception of a spindle 12 through the medium of which the sheave 110 is removably secured in a carrier 13; the said spindle having a handle 14 at its upper

end. The carrier 13 comprises an intermediate portion 15, a lower comparatively short arm 16 and an upper arm 17; the latter being flexibly or loosely connected at its 5 forward end to the upper portion of the pole or upright 4. It will be manifest from this that by reason of the construction and arrangement of the sheave and sheave-carrier the sheave will rest in pendent position with 10 its large portion lowermost and consequently there is no liability of the bight of the line or cable slipping off the sheave. It will also be understood in this connection that the lower large portion of the sheave projects 15 beyond the lower arm of the sheave-carrier and that in consequence the pieces of clothes as they pass around the sheave are not liable to interfere in any degree with the free operation of the apparatus. On the other 20 hand, the pieces of clothes depend out of the way while they are passing about the sheave and hence interference of the pieces of clothes with the operation of the apparatus is precluded, and, at the same time, 25 there is no liability of the pieces of clothes contacting with and being soiled by the sheave or the sheave-carrier. It will also be noticed here that the comparatively long upper arm of the carrier enables the pendent 30 pieces of clothes to freely pass between the sheave and the adjacent support.

In practice, the drum is manipulated to take up the wire portion of the line or cable to pay out the rope length or portion thereof. 35 Then when the first or forward part of the rope length emerges from the casing the operator fastens a piece of clothes thereon, and this operation is continued step by step until the rope length extends from the casing to 40 the sheave and back to the casing, with pieces of clothes thereon. By the time this operation is carried out the first-placed piece of clothes will be dry, and the operator may therefore continue the operation by removing 45 such piece of clothes, feeding the line or cable, and placing and fastening a fresh piece of clothes upon the outgoing length of the line or cable. From this it follows that by preference the rope length of the cable

will be longer than double the distance between the casing and the sheave. It will also be noticed in this connection that by virtue of the arrangement of the pendent sheave to the casing and the apertures in the front wall of the latter, the clothes depending from the outgoing length of the cable will not interfere with the clothes pendent on the return length of the cable. On the other hand, one length of the clothes will be separated by an intervening space from the 60 other length of clothes and hence the prompt and thorough drying of the clothes will be promoted.

After the completion of a clothes drying operation, the drum is manipulated to take up the rope length and to pay off the wire length, when, as will be readily appreciated, the rope length will be protected in and by the casing and the deposit of dust and dirt thereon, and, at the same time, the wire 70 length will be so arranged in exposed position relative to the casing and sheave that the placing of clothes on the cable may be commenced just as soon as the movement of the wire length into the casing is initiated. 75

Having described my invention, what I claim and desire to secure by Letters Patent, is:

A clothes drying apparatus comprising a protecting casing, a drum mounted within 80 the casing on a horizontal axis and arranged at a position above the lower end of the casing, a pulley arranged a considerable distance away from said casing and an endless cable having a portion of its length wound about said drum and having a portion of substantially equal length extending in a 85 double line out of said casing to said pulley and engaging the latter, said pulley being mounted to permit the cable with clothes attached thereto to be moved around the same. 90

In testimony whereof I affix my signature in presence of two witnesses.

EDWARD P. LE COMPTE
